UNITED STATES PATENT OFFICE.

DUNCAN D. McBEAN, OF NEW YORK, N. Y.

TUNNEL CONSTRUCTION.

1,151,958.

Specification of Letters Patent. Patented Aug. 31, 1915.

Application filed May 27, 1914. Serial No. 841,228.

To all whom it may concern:

Be it known that I, DUNCAN D. McBEAN, a citizen of the United States, residing at New York, in the county and State of New York, have invented certain new and useful Improvements in Tunnel Construction, of which the following is a full, clear, and exact description.

This invention is an improvement in methods of unwatering and excavating material below water level in the installation and construction of structures, such as tunnels and sewers, that are built above or on the water level, or the surface of the material to be excavated, and for lowering the same into place step by step as the material beneath them is removed.

The improvements are also applicable to the excavation below water level of material for the erection of such structures as dry-docks, and for the deepening of river and channel bottoms, but in the present application the invention disclosed and claimed is concerned only with and will be described as applied to the construction and installation of tunnels and sewers.

The invention subject of my present application involves novel methods whereby in excavating through water-bearing material, either on shore or in river or channel bottom, the hydrostatic pressure on the outside of the sheeting which I place upon the banks on the sides and ends of an excavation, is neutralized or equalized by the provision of the same hydrostatic pressure against the inside of the sheeting above the bottom level of the structure that is being lowered, and whereby there will be provided on the inside of the sheeting which is below the level of the bottom of the structure, a body of air under sufficient pressure to equal the hydrostatic pressure that exists against the outside of that part of the sheeting, thereby preventing the water, quicksand and other flowing materials from entering the excavated space from under the sheeting, and thereby reducing the pressure on the outside of the sheeting to that due to the difference between the weight of earth and that of water.

My invention further resides in novel methods whereby structures, such as lengths of tunnel or sewer built at the surface of the water may be expeditiously and economically sunk into place through water-bearing material on shore or in river bottom, and

lessen the friction between it and the banks while it is being lowered, although the structure is used as a support for the banks.

Finally, my invention involves such methods as shall provide for the floating of the structure after it has been sunk to the required depth, whereby it is free to be moved into the exact grade and alignment required.

In the accompanying drawings I have illustrated my improved construction and the methods or processes by which it is installed.

Figure 1 is a vertical transverse cross-section of a double tube tunnel structure and the appliances used in connection therewith, in the process of lowering it to the desired level. Fig. 2 is a similar section showing the conditions and relations of the tunnel and its appurtenances after a certain amount of excavation has been accomplished. Fig. 3 is a similar view showing the end of a tunnel section after some of its appurtenances have been removed and in condition to receive the end of the next adjacent structure. Fig. 4 is a horizontal sectional plan showing the arrangement of sheeting surrounding the structure and the intermediate devices employed therewith. Fig. 5 is an enlarged sectional detail illustrating the same features. Fig. 6 is an enlarged detail of the section of Fig. 1. Fig. 7 is a detail view of the sheeting, showing the means of joining the sections of the same. Fig. 8 is an enlarged sectional detail of the joint between the beams and planking of different sections. Fig. 9 is a view, partly in elevation, and partly in section, illustrating the method of adding a new section of tunnel to one already in place. Fig. 10 is a horizontal section of the same. Fig. 11 is an enlarged detail showing the means for uniting two sections. Fig. 12 is a cross-section showing a completed section before all of the sheeting and supports are removed.

Similar numerals of reference indicate corresponding parts in all the figures.

The tunnel structure may consist of one or more tubes and may be built at any convenient point in the desired lengths, which may be two hundred feet or more, and floated or carried to the place where it is to be sunk in place. It is composed of iron or steel uprights 1 and transverse roof and floor beams 2, 3, all secured together to form a skeleton frame. To the outside of each of the steel uprights 1 on the exterior of the structure,

there is bolted a vertical plank to which horizontal tongued and grooved water tight planks 4 are pinned with maple pins, thus forming a water proofing which incloses the sides of the skeleton frame. The spaces between the steel uprights and the transverse roof beams, are filled solid with concrete 5. The waterproofed planking is placed on the top of the roof beam and intermediate concrete and joined to the waterproofing on the sides, and an outer covering of concrete 6 is laid over the waterproof planking on the top, to protect it from the attacks of marine insects in case it should be exposed directly to the water.

Extending completely through the structure is an airlock shaft 8, and extending only into the structure is a second air-lock shaft 9 for the purposes which will hereinafter appear. Through stuffing boxes in the temporary floor 4 there extend cylindrical steel piles 10 and the pipes of a mud or sand pump 11. Otherwise each section of tunnel is inclosed on all sides, the ends being closed by temporary bulk-heads 12 in order to make the structure water-tight.

The method of installing a single section of tunnel thus constructed is as follows: I-beams or columns 13 of a length sufficient to 30 extend from the top to near the bottom of the structure are placed vertically at intervals along the sides and ends of the same and secured in position to the upright beams 1 by bolts passing through their inner 35 flanges, the space, if any exist, between the inside flanges of the vertical column 13 and the sides of the structure, being filled with timber or metal plates. A second set of very 40 much heavier I-beams or columns 14 of a length sufficient to extend from near the level of the bottom of the structure to about one foot above its roof or top, are placed vertically outside of and opposite to the inner 45 beams 13 with a space of a few inches between the two which is maintained by wedges 15 and braces 34 placed between them at intervals of a few feet of their height. These outside beams 14 are held in place by 50 bolts 16 passing through the outer flanges of the inner and the inner flanges of the outer beams. A pair of vertical beams on one side of the structure are placed opposite a pair on the other side and the tops and bottoms of the outer beams are united by braces 17 extending 55 across between them above the top and beneath the bottom of the structure. The lower ends of beams 14 are secured by flanges 22 and bolts 23 to a heavy planking 24 as shown in detail in Figs. 5 and 6 and 60 the space between this planking and the base of timber 25, to which the lower ends of beams 13 are similarly secured, as shown in the same figures, is closed with I-beams 26. Consecutive tiers, one above the other and a 65 few feet apart, of horizontal walings or

ranges 18 are placed continuously along the sides and across the ends of the structure, and a few inches outside of the vertical beams 14 to which they are temporarily attached, as by bolts or otherwise. The lower 70 tier of walings 18 is placed so as to be on a level with the heavy planking 24. Between the tiers of walings 18 there are placed at intervals vertical braces 19 and tie-rods 20 and fixed rollers 21 are secured to the inner 75 upright faces of the walings opposite to and contiguous with the outer flanges of the vertical beams 14, and the few inches of space between the bottom of the lower tier of horizontal walings and the bottom of the horizontal planking 24, to which the beams 14 are secured, are closed by planks 26 placed under them and overlapping them both. Vertical planks of sheeting 27, the length of which is substantially equal to the depth of 80 excavation required, are placed close together on the outside of the tiers of horizontal waling 18 to which they are temporarily tacked. In order to secure a good and water tight joint between the sections of 85 this sheeting I have adopted the form of joint shown in Fig. 7, in which 43 is an iron or steel plate set in the edge of one section of sheeting and 44 are similar plates extending over a recess and secured to the edge of the 90 opposite section to form a socket in which a projection on the plate 43 may enter and slide when the two sections are associated. To support the sheeting and guide it while 95 being driven, there are placed on the outer side tiers of horizontal walings 28, which are temporarily held in place by bolts passing through them, through the sheeting and the inner walings 18. The insertion of the sheeting 27 may be postponed until after the 100 structure is floated, the space therefor between the outer and inner tiers of walings being maintained by blocking inserted at intervals between the two. The structure and its appurtenances as thus assembled is 105 launched or floated, generally by sinking the float on which the parts described above were assembled, and towed to a point immediately over its intended site. A few piles 32 are then driven down through stuffing 110 boxes provided for them in the planking 24 for several feet into the material to be excavated, and collars 33, as shown at the left in Fig. 1, are secured to them by divers at the 115 elevation to which it is intended to at first 120 lower the structure.

The buoyancy of the structure is overcome either by introducing into it loosely on its temporary flooring 4 a portion of the material that will be subsequently utilized to 125 fill in the spaces between the floor beams, or by permitting sufficient water to enter the same, or by adding weight, in control of derricks, onto the structure sufficient to sink it. Blocking 30 is placed at intervals on the 130

material to be excavated upon which the bottom plank 26 rests, and the structure is in this way supported on the bottom. After the structure is alined as nearly as possible, 5 the piles 10 are then driven for a few feet into the material under the same and collars 29 are then adjusted, by divers, on such piles in contact with the flooring 4, so that the entire structure will be supported at 10 proper levels in its correct position. When the tunnel section has been thus adjusted and alined, the sheeting 27 is detached from its temporary union with the walings and driven entirely around the structure for a 15 few feet into the material to be excavated. Simultaneously, air is pumped under the floor of the structure, which, as will be seen from the above description, forms a substantially air-tight compartment, and sufficient 20 water is permitted to enter the structure itself to give it sufficient weight to withstand the pressure of air which it is necessary to have under the flooring. Workmen then descend from the surface, through the 25 air-lock shaft 8 which passes through stuffing-boxes in the top and bottom of the structure, and excavate the material under the flooring. This is accomplished either by introducing water, as through a pipe 31, 30 and pumping out the sand and mud therewith by the pump within the tunnel section, or by hoisting out the material in buckets through the air-lock shaft 8. The material is thus excavated for a depth of several feet 35 when walings 18, as shown in Figs. 2 and 3, carried down into or previously stored in the compartment under the floor, are placed against the sheeting 27. They may be temporarily held in position by braces between 40 them and the piles 32, and on their inner faces are fixed rollers corresponding to those above described. When the excavation in this way has been completed, the collars on the piles 10 and 32 are lowered to the level 45 of the bottom walings, and water is admitted thereto through the pipes 31 or by the removal of planks 26^a. For this purpose the air pressure under the floor is reduced, while that in the structure is increased. 50 The structure is caused to slowly slide down between the fixed rollers 21 on the walings, and the vertical beams 14, until it rests upon the blocking or planking and collars prepared for its reception, and a 55 water-tight compartment again formed by the stoppage of the narrow space between the walings and the planking. The water in this compartment under the floor is then forced up into the tunnel proper by decreasing 60 the air pressure in the latter and increasing that under the floor. These operations of excavating and lowering the structure are repeated until the excavated recess is of the required depth, at which the structure is 65 to permanently rest. If at such a time it is

found not to be in true alinement, the piles 10 and 32 are withdrawn or cut, or burned off, and the I-beams 13 and wedges removed whereupon the structure will be virtually afloat in the space between the vertical 70 beams 14 and the cross beams 17. By the adjustment of the wedges 15, or otherwise, the structure is then forced into exact alinement with the section previously in place. When this has been done, air is pumped into 75 the structure until the pressure is equal to the hydrostatic pressure at the level of the temporary floor 4. This floor is then removed and the pressure increased within the structure until it equals the hydrostatic pressure at the level of its foundation, which is then prepared, a new water-tight flooring 35 laid on the cross-beam 17 and the spaces above the floor and between the horizontal beams filled in with concrete and the structure completed. The horizontal planking 80 24 is then detached by divers from the beams 14, the sheeting 27 drawn and all of the appliances utilized in the construction and installation of the tunnel removed or 85 allowed to float up. After each section of tunnel is completed the air-lock shafts 8 and 9 are removed.

The above is the complete method of installing a single section of tunnel and no 90 other steps are necessary where the entire structure consists of but a single section. In case, however, that the finished structure is made up of two or more such sections, provision must be made for connecting them 100 together into an integral whole. This feature of my invention is illustrated in Figs. 2, 3, 9, 10 and 11. As soon as a section is completed and in readiness to be connected with another, divers build a plank bulk-head 105 40, Fig. 3, out from the side walls of the section to the main sheetings 27. The outer surface of these bulkheads 40 are built on a true plane with the bulkhead 12 at the end of the section. In lieu of the beams and 110 walings, which are necessary at the outer ends of the sections, and which are removed after the bulkheads 40 have been built, I use an angle iron 41 which is secured horizontally across the face of the bulkheads 12 115 and 40, upon which the bottom of the end of the new section rests as shown in Fig. 9. This angle iron is removed and attached to the bulkheads at lower levels as the material under the new section is excavated and 120 the latter lowered. When the new section is lowered to subgrade and put in alinement, the bulkheads 40 are removed, and the side and top planking 4 at the ends of the abutting sections are joined together with planking 37 and 39 bolted together, as shown in 125 Fig. 11, which is slipped over the flanges of adjacent steel uprights 1 and transverse roof beams 2. Planking 36 is then pinned to planking 37. When this has been done, air 130

under pressure is introduced between the bulkheads of the sections, the latter are removed, then the spaces between the beams are filled in with concrete 5, thus completing 5 the union of the sections.

When a tunnel or sewer is to be constructed on shore, and where the material to be excavated is water bearing, the procedure above described will be modified somewhat 10 to meet the change of conditions involved. In such cases the structure and its appurtenances above set forth are assembled above the surface of the water in the ground to be excavated, and the space below the water 15 level between the driven sheeting 27 and the structure, as well as that over the latter, as it is lowered into the ground, is kept filled with water up to the level of the water in the ground outside of the sheeting, but as 20 this supply of water must not be permitted to flow in under the sheeting, it may have to be brought from an outside source. When the depth of the excavation below the level of the outside water is greater than the 25 height of the structure, through-bracing between the walings on the opposite sides must be introduced over the structure, but otherwise the procedure is the same as that for subaqueous tunnels described above.

30 The invention herein set forth constitutes a radical departure from the established practice and methods heretofore adopted and presents many advantages which none of the latter possess. In the building of 35 subaqueous tunnels it permits the excavation, whatever the material, to be effected at a much less cost than it can be done in any other way. The quantity of material to be removed is reduced to a minimum, and if it 40 be soft, it may be pumped out instead of being dug and hoisted to the surface. The possibility of placing the pumps in the water-tight compartments or sections of the structure at a depth perhaps many feet below the surface of the water, increases their 45 efficiency many fold, because of the hydrostatic pressure due to the depth operating to force material into the pumps, whereby there will be a much larger percentage of 50 material carried along with the water through the pump than if the latter had only the vacuum which it creates to draw material to and into itself. In case where rock is encountered, it may be unwatered 55 and blasted and then excavated at a much lower cost than by the ordinary methods.

In the building of tunnels or sewers in 60 streets between buildings, the foundations of which rest on sand or water-bearing material, the tunnel structure may be carried to a level well below that of the foundations without disturbing either the sand or the water in the material outside of the sheeting which retains the banks of the excavation. 65 It makes cut and cover work an absolutely

safe and sure method of making an excavation to any depth under one hundred feet.

Having now described my invention, what I claim is:

1. The method of constructing subaqueous 70 tunnels which consists in sinking the same in partially completed condition on to the material to be excavated and over the position which it is to occupy, undermining and removing the material under and around 75 the same, gradually lowering the structure into the excavated space to the desired level, and floating it at such level into the exact position in which it is to permanently remain.

2. The method of constructing subaqueous 80 tunnels which consists in sinking the same in partially completed condition on to the material to be excavated and over the position which it is to occupy, driving sheeting 85 around the structure to form a water-tight compartment under the same, excavating the material within the sheeting, lowering the structure to the desired level, and then floating it within the sheeting to the exact 90 position in which it is to permanently remain.

3. The method of constructing subaqueous 95 tunnels which consists in sinking partially completed lengths of the same on to the material to be excavated and over the positions which each is to occupy, excavating the material under and around the lengths, gradually lowering each length into the excavated 100 space to the desired level, floating it into exact alinement with the length previously completed, and uniting it thereto.

4. The method of constructing subaqueous 105 tunnels which consists in sinking the same in partially completed sectional lengths to 110 the material to be excavated over the positions which each is to occupy, driving sheeting around each section and forming a water-tight compartment under the same, excavating the material within the sheeting, 115 lowering the sections into such space to the desired level, then floating the sections within the sheeting into exact alinement with the previously completed section and uniting it thereto.

5. The method of constructing subaqueous 120 tunnels which consists in sinking a partially completed section of the same onto the material to be excavated over the position which it is to occupy, driving sheeting 125 around the same, and forming thereby a water-tight compartment under it, guiding the section through the sheeting when the material within the same has been excavated, and floating it into alinement with the previously completed section when it has reached the desired level.

6. The method of constructing a sectional 130 subaqueous tunnel, which consists in sinking a partially completed section on to the ma-

terial to be excavated over the position which it is to occupy, driving sheeting around the section and forming under the section within the sheeting a water-tight compartment, excavating into such compartment, lowering the section into the same until it reaches the proper level, releasing the section from the pressure on the sheeting and floating it into alinement with a previously completed section, and uniting it to the same.

7. The method of constructing a sectional subaqueous tunnel which consists in sinking a partially completed section onto the material to be excavated over the position which it is to occupy and supporting it in such position by piling, driving sheeting around the section and forming under the same a water-tight compartment, excavating into such compartment, lowering the section into the same step by step until it reaches the desired level, withdrawing the piling and floating the section into alinement with a previously completed section and uniting it thereto.

8. The method of constructing a sectional subaqueous tunnel, which consists in sinking each partially completed section successively onto the material to be excavated over the position which it is to occupy and supporting it at such level by piling, driving sheeting around it and forming under it a water-tight compartment, excavating into such compartment, lowering the section into the same step by step as the excavation proceeds until it has reached the desired level, withdrawing the piling, floating the section into alinement with a previously completed section, uniting the sections, and removing the sheeting.

9. The method of constructing a sectional subaqueous tunnel, which consists in sinking each partially completed section successively onto the material to be excavated over the position which it is to occupy, and supporting it at such level by piling, driving sheeting around it and forming under it a water-tight compartment, excavating into such compartment, lowering the section into the same step by step as the excavation proceeds, until it has reached the desired level, then floating the section into alinement with a previously completed section,

removing its temporary floor and building the foundation and permanent flooring 55 therein.

10. The method of constructing a subaqueous tunnel which consists in sinking it in a receptacle formed by sheeting driven around it, dividing the said receptacle by a water-tight partition at or near the level of the bottom of the structure, excavating the material below such partition to permit the structure being lowered to the required depth and leaving above said partition between the structure and the sheeting sufficient water to equal the pressure from the water on the outside of the sheeting.

11. The method of constructing a sectional subaqueous tunnel which consists in sinking sections of the same into receptacles formed by sheeting driven into the material to be excavated, forming in such receptacles a water-tight compartment under each section, excavating into such compartment, 75 lowering the section step by step therein and admitting such water thereto when the section has reached the desired depth to float the section into exact alinement with another previously completed.

12. The method of constructing a sectional subaqueous tunnel which consists in driving sheeting into the material to be excavated around all four sides of a section and forming under the section a water tight 85 compartment from which the material may be excavated, the sheeting being at such distance from the section as to leave a water space between it and the said section.

13. The method of constructing subaqueous tunnels, which consists in sinking a partially completed section of the same onto the material to be excavated over the position which it is to occupy, placing sheeting around the same, guiding the section between the walls of sheeting when the material within the same has been excavated, and floating it into alinement with the previously completed section when it has reached the desired level.

In testimony whereof I affix my signature in the presence of two subscribing witnesses.

DUNCAN D. McBEAN.
